UNITED STATES PATENT OFFICE.

HERBERT H. HULL, OF CLEVELAND, OHIO.

FAUCET AND FILLER FOR CANS.

SPECIFICATION forming part of Letters Patent No. 364,821, dated June 14, 1887.

Application filed February 21, 1887. Serial No. 228,452. (No model.)

To all whom it may concern:

Be it known that I, HERBERT H. HULL, of Cleveland, in the county of Cuyahoga and State of Ohio, have invented certain new and useful Improvements in Fillers and Faucets for Oil-Cans, of which the following is a specification.

This invention relates to filling necks and faucets for oil and other similar cans, and has for its object to provide for turning the neck with its spout around to bring the spout over the body of the can when desired.

To this end the invention consists in constructing the lower edge of the neck with a flange and surrounding said flange with a ring or collar secured to the head of the can, and leaving the flange loose therein, so that the neck may be revolved, substantially as hereinabove described, and pointed out in the claim.

In the accompanying drawings, Figure 1 is a perspective view of my improved filling-neck, the dotted line showing the same as it appears with the spout turned over the can. Figs. 2 and 3 are vertical sections of the same, showing two modes of constructing the turning joint.

A, in the several figures, is a neck for metal cans, having indented screw-threads in its sides, at one side of which is attached a discharge-spout, B.

C is the hole in the top of the can, over which the neck A sets, and the edge of said hole is slightly upturned, as seen in Fig. 3, where said hole forms the valve-seat. The lower edge of said neck has a narrow flange, a, turned outward.

D is a ring or collar having a beaded groove, d, pressed up or formed upon it, into which the aforesaid flange a is loosely fitted. Said ring or collar D is soldered to the top of the can, and thus the neck is fixed over the said hole C in the can and is free to revolve, as shown in Fig. 3. Said ring D, as seen in Fig. 2, extends inward from the bead or groove d and has its inner edge slightly upturned to form the valve-seat. Within said neck is contained a chambered stopper, E, in the bottom of which is fixed a cork or other suitable gas-
ket, F, which, when the stopper is screwed down, rests upon the slightly-upturned edge of the hole C, and thus tightly closes the opening into the can. In the bottom of said cham-

bered stopper is made a hole, G, of somewhat smaller diameter than the opening C, and in the side wall of the stopper is made a hole, H, which registers with the spout B. Within the chambered stopper is contained a valve and valve-operating mechanism for closing said opening in the bottom of the stopper, as follows: I is a screw-threaded stem playing in a screw-threaded socket, i, on the top of the stopper E, and is provided on its lower end with a disk, J, having a flange, j, which holds a disk of cork or other suitable material, K, which covers and closes the opening G in the bottom of the stopper. L is a thumb-disk on the top of the screw-stem I for turning it by.

The operation of this is as follows: The screwing down of the stopper E not only closes the opening into the can, but it also securely holds the neck from turning, and thus obviates the liability of the neck turning when not required. Now, when it is desired to turn the neck, the stopper may be slightly loosened up and the neck turned to either side required. The valve and the valve mechanism work independently and are not affected by the turning of the neck. This improvement also admits of the employment of a long spout, which the old method forbids, because the neck and spout, being permanently fixed, would not admit of a spout that projected beyond the edge of the can, for in the handling and shipping of the can a projecting spout is very liable to be bent or broken.

Having described my invention, what I claim, and desire to secure by Letters Patent, is—

The combination of a neck having a flange at its base and loosely secured to the can over the opening therein by a ring or collar surrounding and embracing said flange, and a chambered stopper having a hole in its bottom controlled by a valve provided with a screw-threaded stem playing through the top of the stopper, the stopper also having a hole in its side registering with a spout in the neck, and also a packing in the bottom for tightly closing the opening in the can, constructed and arranged to operate substantially in the manner and for the purpose specified.

HERBERT H. HULL.
